STEAM IRONING ATTACHMENT FOR FLATIRONS

John N. Polivka, Minneapolis, Minn., assignor to
General Mills, Inc., a corporation of Delaware

Application June 11, 1948, Serial No. 146,918

Term of patent 14 years

(Cl. D49—6)

To all whom it may concern:

Be it known that I, John N. Polivka, a citizen of the United States, residing at Minneapolis, in the county of Hennepin and State of Minnesota, have invented a new, original, and ornamental Design for a Steam Ironing Attachment for Flatirons, of which the following is a specification, reference being had to the accompanying drawing, forming part thereof.

In the drawing

Fig. 1 is a top plan view of a steam ironing attachment for flatirons showing my new design.

Fig. 2 is a side elevational view of the attachment, in combination with an electric flatiron, the latter being shown in dotted outline for purposes of illustration.

Fig. 3 is a bottom plan view thereof.

The side not shown is substantially the same as the one shown and the dominant features of my design reside in those portions shown in full lines.

I claim:

The ornamental design for a steam ironing attachment for flatirons, as shown and described.

JOHN N. POLIVKA.
